CLAIM

The ornamental design for a replaceable blade, as shown and described.

DESCRIPTION

FIG. 1 is a perspective view of the replaceable blade;
 FIG. 2 is a front elevation view thereof, the rear elevation view being a mirror image thereof;
 FIG. 3 is a left elevation view thereof;
 FIG. 4 is a right elevation view thereof;
 FIG. 5 is a top plan view thereof; and,
 FIG. 6 is a bottom plan view thereof.
